UNITED STATES PATENT OFFICE.

ROBERT BOYLL, OF TERRE HAUTE, INDIANA.

ELECTRIC WAX SEALER.

1,406,526.

Specification of Letters Patent. Patented Feb. 14, 1922.

Application filed October 19, 1920. Serial No. 417,904.

To all whom it may concern:

Be it known that I, ROBERT BOYLL, a citizen of the United States, residing at Terre Haute, county of Vigo, State of Indiana, have invented certain new and useful Improvements in Electric Wax Sealers; and I do hereby declare the following to be a full, clear, and exact description of the invention, such as will enable others skilled in the art to which it appertains to make and use the same.

The present invention relates to improvements in electric wax sealers, and more particularly refers to an improved instrument for the making of wax seals on letters, packages, etc.

An object of the invention is to provide an improved wax sealer in which the combined operations of melting, depositing and stamping the wax will all be performed through a single agency which is driven through two complete strokes including the entire cycle of operation.

Another object of the invention resides in providing an improved wax sealer of a simple and inexpensive construction with a minimum of parts grouped compactly together and forming an attractive instrument.

A still further object of the invention is to provide a machine in which a minimum amount of the electric current will be consumed in the operation of heating the wax and in which the operation of the machine will be simple and uniformly effective.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a vertical sectional view through an improved electric wax sealer constructed in accordance with the present invention and showing the parts in the initial position;

Fig. 2 is a similar view taken at right angles to Fig. 1;

Fig. 3 is a view similar to Fig. 1 showing the parts in a second position;

Fig. 4 is a view similar to Fig. 2 and

showing the parts in the second position referred to;

Fig. 5 is also a vertical sectional view of the instrument in its final position; 55

Fig. 6 is a similar view taken at right angles to Fig. 5 and showing the parts in a similar position;

Fig. 7 is a cross sectional view on an enlarged scale of a portion of the wax holder; 60

Fig. 8 is a sectional view taken on the line 8—8 in Fig. 7;

Fig. 9 is a side view of the delivery jaws;

Fig. 10 is a vertical sectional view through the jaws shown partially open; and 65

Fig. 11 is a horizontal sectional view taken on the line 11—11 in Fig. 9.

Referring more particularly to the drawings, 1 designates a casing having a suitable base 2 by which it rests upon a suitable support, and 3 represents an extension tube erected on the top of the casing 1. An opening 5 in the top 4 of the casing serves to set up a communication between the interiors of the casings and extension tube 70 3. A tube or holder 6 for a stick of wax is fitted to reciprocate vertically in the extension 3 and is provided with a flange 7 at an appropriate point for cooperating with the internal shoulder 8 made at the top of 75 the extension 3 whereby to limit the upward movement of the tube or holder 6 in which it is influenced by a coil spring 9 having its upper end engaging beneath the flange 7 and its lower end taking against an internal 80 flange 10 projecting from and into the lower portion of the extension 3.

A top 11 is hinged to the tube or holder 6 as represented at 12 and serves to give access to the interior of the same for the purpose of inserting a stick of wax. As shown in Figs. 1 and 2, the upper face of the cap or cover 11 is suitably rounded for convenient engagement with the hand of the operator in order that he may depress the tube or 90 holder in the manner and for a purpose later explained.

Arms 13 in appropriate numbers are riveted or otherwise secured to the lower end of the tube or holder 6 and project beyond the 100 lower end thereof. These arms 13 in the instance shown in the drawings are four in

number and are situated at 90° apart so that they fulfill the function of grasping and retaining the wax stick in place, while at the same time permitting of the active circulation of air about the same and about the lower parts carried thereby. A ring 14 passes about within the strips 13 at their medial portions in order to reinforce the same and to prevent their spreading. The 10 arms at their lower ends carry a head 15, shown more particularly in Figs. 7 and 8, and which is either of rectangular or cylindrical construction as may be required to receive the various cross sections of the wax 15 stick. The head 15 has pivoted therein a pair of jaws 16 and 17, the pivot points being indicated at 18 and 19 and being situated at the upper divergent ends of the jaws. The jaws are each substantially triangular in 20 side elevation or appear scoop shaped, they being normally held together along their meeting edges in order to form a closed trough in which the wax at the lower end of the stick may be melted as presently referred to.

Lugs 20 on the jaws 16 and 17 are provided to receive the ends of coil springs 21 serving to yieldably hold the jaws together in the manner indicated in Fig. 9, but permitting of their opening, as illustrated in Fig. 10.

The jaws 16 and 17 are provided with perforated lugs 22 and 23 to receive electric heating elements 24 and 25 in which are included suitable resistance coils of a character that are well-known and form no part of the present invention, so that they are not particularly illustrated.

The electric heaters 24 and 25 normally 40 occupy the position shown in Fig. 1 in which they swing down by gravity away from the inclined faces of the jaws 16 and 17. Webs 26 and 27 project at right angles outwardly from the electric heating elements 24 and 45 25 and receive the ends of chains or other suitable flexible connections 28 and 29. Perforated ears 30 and 31 extend from the interior walls of the casing 1 at a suitable elevation and receive the opposite ends of the 50 chains 28 and 29. These chains are of appropriate lengths to subserve certain functions hereinafter pointed out.

Contact fingers 32 and 33 project outwardly from the free end of the electric heating elements 25, as shown in Figs. 1 and 2. These two contact fingers are connected to opposite ends of the resistance coil. The finger 32, for instance, carries current from an exterior source into the coil, while the 55 finger 33 serves to carry off the current after it has traversed the windings of the heating element.

Cooperating contact fingers 34 and 35 project downwardly from the head 15 so as to 60 be engaged respectively by the fingers 32

and 33 when the heating element 25 is caused to swing up against the inclined faces of the jaws 16 and 17 in which position it is illustrated in Fig. 3. The fingers are preferably of spring material in order that they 70 may come into a yielding engagement and form an effective contact. The opposite heating element 24 is provided with similar contact fingers 36 which co-act with further contact fingers 37 depending from the 75 head 15.

The current is received from the source through a lead 38 which is connected to a binding post 39 near the lower end and at one side of the extension 3. A contact plate 80 40 is in connection with the binding post 39 and is insulated from the wall of the extension. Such contact plate 40 projects in the path of a companion contact plate 41 carried by the wax holder or one of its arms 13, the meeting edges of the plates 40 and 41 being beveled in order to facilitate their engagement when the holder is depressed to the position shown in Fig. 3. The contact plate 41 is likewise insulated as indicated 85 from the surrounding members of the wax holder and it has connection with a conductor 42 which extends down within the arm 13 with which the plate 41 is associated.

The conductor 42 is an extension through the arm 13 of the contact finger 34 as will be seen in Fig. 2. The opposite contact finger 35, also seen in Fig. 2, is a prolongation of a conductor 43 which is insulated from and passes about within the head 15, 100 as shown in Fig. 7, to the opposite side where it connects with the contact finger which supplies current to the resistance coil in the electric heating element 24. The current, after passing through the coils of the heating element 24, will pass through the fingers 36 and 37 and to a contact plate 44 similar to the plate 41. The plate 44 cooperates with a companion plate 45 associated with a binding post 46 with which the opposite wire 47 of the source of current is connected. Of course, other circuit closing means may be used.

An impression producing die 48 is carried on the lower ends of arms 49 pivoted 115 as at 50 to the extension 51 of the arms 13, as seen in Figs. 6 and 8. The arms 13 are offset at connection with the head 15. The arms 49 are provided with a right angular piece 52 carrying a pin 53 for engagement in the notch 54 produced in the lower end of the lever 55. This lever is fulcrumed as indicated at 56 in the upper portion of the casing 1 near the wax holder and is adapted to be engaged by the beveled lower edge of 120 a toe 57 formed on a handle 58 which is pivoted at 59 within the casing 1 and operates in a slot 60 made in its top.

Beneath the die 48 are a pair of swinging plates 61 and 62 pivoted at 63 and 64 within 130

the casing 1 and adapted to hold oiled pads 65 and 66 in such a way that they are presented to the lower face of the die 48. Jointed arms 67 and 68 are coupled between the plates 61 and 62 and the pivot pins 50 of the arms 49 for the purpose of raising the plates to the horizontal position after they have been depressed, as shown in Fig. 4. A coil spring 69 is coupled between the lever 55 and the casing 1 in order to draw the lever normally downward to the position indicated in Fig. 3 when it is unrestrained by the toe 57. A spring latch 70 is carried by the support of the extension 3 and projects through an opening 71 made therein to permit the latch to project into the path of the flange 7 on the tube 6. This is shown in Fig. 4.

The operation of the invention is substantially as follows. The parts are normally in the condition shown in Figs. 1 and 2. The lid 11 is lifted, and a bar of wax or analogous material inserted into the holder 6 and pushed down therein until the lower end of the wax bar enters the trough formed by the pair of coacting jaws 16 and 17. The lower portion of the bar will be confined by the arms 13 and ring 14 while exposing the majority of its surface to the air circulating through the interior of the apparatus.

When it is desired to seal an envelope, package, or the like the entire instrument is placed with its base 2 over the package so that the upper portion of the package to be sealed is exposed to the action of the interior parts. The tube 6 is then depressed, by engagement of the hand with the upper surface of the cover 11, to the position shown in Figs. 3 and 4, the latch 70 being projected into the casing so as to engage with the flange 7 and hold the parts in this condition for a suitable interval of time. This interval of time is that necessary to the heating and melting of the desired quantity of wax.

The downward movement of the holder to this position causes the chains or connections 28 and 29 to be brought to a taut condition such as will swing the electric heating elements 24 and 25 about their pivot points 22 and 23 up against the inclined faces of the jaws 16 and 17. The contact fingers will be thus closed and the circuit completed through the coils which will thus transmit heat through the comparatively thin metallic walls of the jaws to the lower end of the wax bar within the trough.

A few seconds only will be required to melt a suitable quantity of the wax which will flow down into the closed apex of the delivery jaws and will be held there until the jaws are opened. This opening of the jaws is accomplished by a further downward movement of the holder 6. This movement

70 accomplishes the opening of the jaws, for instance to the position shown in Fig. 10 by reason of the pull exerted on the pivot points 18 and 19 by the taut chains or connections 28 and 29 acting through the electric heating elements.

The downward movement of the various parts as aforesaid will strike and shift the plates 61 and 62 out of the way so that the melted wax may issue through the opened 75 lower ends of the jaws on to the package placed beneath the machine.

During all of these movements the impression die 48 will be swung out to the position indicated in Figs. 3 and 4 so as not to 80 interfere with the depositing of the melted wax on the package. This swinging of the die is accomplished through the medium of the lever 55 which clings in the pin 53 of the projecting piece 52 and therefore causes 85 the swinging of the die about its pivots 50. The die extends outwardly through an opening 72 made near one side of the casing wall for this purpose.

After the wax is delivered to the package, 90 the holder itself is allowed to ascend, the latch 70 meantime springing out of the opening 71 so as not to interfere with the operation of the spring 9 in raising the wax holder. When in the raised position the handle 58 95 is swung over to the position shown in Fig. 5 against the extension 3 causing the toe 57 to engage the adjacent portion of the lever 55 and raise this lever whereby to free the notch 54 from the pin 53.

The next operation is to depress the tube 6 a second time. During this second movement the die will remain in advance of the delivery jaws and will descend on to the melted wax lately deposited on the package. The wax will, therefore, acquire the impression contained on the die face. After the impression is made the holder is ready to ascend a second time, the pin 53 reengaging in the notch 54 of the lever 55, and by 100 swinging the handle 58 to the initial outward position, the apparatus is put in condition to be subsequently operated.

I have described preferred and satisfactory constructions, but it will be obvious 115 that various changes and modifications may be made without departing from the spirit of the invention, provided such changes are within the scope of the appended claims.

I claim:

1. An improved wax sealer comprising a holder for the wax, movable jaws carried by the holder forming a trough for the melted wax, means to normally retain said jaws closed, heating means movably attached 120 to said jaws and adapted to be shifted up against the latter whereby to transmit heat to the interior of the trough, means whereby said heating means may be moved into contact with the jaws and whereby the jaws 130

may be subsequently opened to permit delivery of the heated wax, and impression means associated with the holding means and adapted to form an impression upon 5 the previously delivered wax, substantially as described.

2. An improved electric wax sealer comprising a support, a holder for the wax movably mounted on the support and biased to 10 an initial inoperative position, delivery means carried by the holder and forming a trough for the melted wax, means to yieldably hold said delivery means closed, movably arranged electric heating means associated with said delivery means and adapted 15 to receive current when moved into contact with said delivery means, connections whereby said heating means may be moved into contact with the delivery means upon the 20 partial movement of the holding means, said connections through the heating means adapted to open the delivery means when the holder is moved a further distance, and impression producing means associated with 25 said holder and adapted to be brought into contact with the melted wax upon the subsequent movement of the holder, substantially as described.

3. An improved wax sealer comprising a 30 support, a reciprocating holder for the wax movably mounted on the support, yieldable means for retaining said holder in an upper position, delivery means carried by the lower end of said holder and forming a trough for 35 the melted wax, yieldable means for maintaining said delivery means normally closed, electric heaters pivotally mounted to said delivery means and normally lying out of contact with the same, connections coupled 40 to said electric heaters for moving the latter against said delivery means when the holder is moved in one direction, switch means for closing circuit through said electric heaters when the same are moved into contact with 45 said delivery means, and impression producing means carried by said holder and adapted to come in contact with the melted wax on a subsequent movement of the holder, substantially as described.

50 4. An electric wax sealer comprising a support, a reciprocating holder for the wax movably mounted on the support, yieldable means for retaining the holder in an initial position, pivoted jaws normally and yieldably held closed and carried by the lower end of said holder, electric heaters pivoted to the lower portions of said jaws and normally diverging away from the jaws, connections coupled to said electric heaters for 55 causing the same to swing against the jaws when the holding means is moved in opposition to its yieldable retaining means, switch means for closing circuit through said electric heaters when the same are moved against 60 said jaws, and impression producing means 65

carried by said holder and movable by the latter on a subsequent stroke into contact with the melted wax, substantially as described.

5. An improved electric wax sealer comprising movable holding means for the wax, means whereby the wax may be heated in such holding means, a die carried by the holding means and adapted to be initially swung out of the path of the holding means, 75 means for greasing said die, and means whereby such greasing means may be moved out of the path of the die, substantially as described.

6. An improved electric wax sealer comprising holding means for the wax, heating means associated with said holding means, a die carried in advance of said holding means, means whereby the die may be initially swung out of the path of said holding means, swinging oil pads for the die, and means whereby the pads are automatically swung out of the path of the die, substantially as described.

7. An electric wax sealer comprising a 90 reciprocating holder for the wax, delivery jaws normally closed and carried by said holder, heating means associated with the jaws and adapted to be put in the heat producing condition by a partial movement of the holder in one direction, an impression die pivotally carried by said holder in advance of the jaws, means placed relatively to the holder for acting on the die to swing the latter out of the path of the jaws on an 95 initial stroke of the holder, and means for displacing said last named means to permit the die on a subsequent stroke of the holder to descend into contact with the previously delivered wax, substantially as described. 100

8. An electric wax sealer comprising a support, a wax holder mounted for movement in the support, means for normally urging the holder to an initial position, normally closed pivoted jaws at the base of the holder for receiving the wax, heating elements pivoted to the lower portions of the jaws and normally lying out of engagement therewith, means attached to the heating elements and to the support for drawing said heating elements into engagement with the jaws when the holder is lowered and for subsequently opening said jaws, contact means closed when said heating elements are moved into engagement with said jaws, and impression producing means carried by said holder, substantially as described. 110

9. A wax sealer comprising a holder for the wax, a support in which the holder is movably mounted, pivoted jaws at the base 125 of said holder, means to yieldingly hold the jaws closed, heating elements pivoted at their lower ends to the lower portions of said jaws, connections between said heating elements and the support adapted to be 130

drawn taut when the holder is lowered, whereby to cause the heating elements to move into engagement with the sides of said jaws, contact means carried by said heating elements and holder adapted to be closed when the heating elements are moved against said jaws, a die swingingly carried by said

holder, means to swing the die out of the path of the jaws on an initial downward movement, and means whereby said die may 10 be allowed to descend in advance of the holder on a subsequent movement, substantially as described.

ROBERT BOYLL.
